[57] ABSTRACT

Condenser apparatus for removing moisture from the

air including a housing for the condenser apparatus, which housing has both a cooling liquid inlet and an air inlet at one end. Within the housing is a stack of discs mounted on a rotatable shaft that has a liquid reservoir at one end and channels that are in liquid flow communication between the reservoir and the discs and arranged such that equal quantities of liquid is distributed to each of the discs during operation of the condenser apparatus. The rotating discs form a cloud of cooling liquid droplets in a condensing chamber within the housing. At the opposite end of the condenser housing from the inlet is an air outlet and a rotatable blower. Located between the blower and the rotatable discs is a rotatable water wheel for collecting entrained liquid droplets before they pass into the blower. Circumferentially around the rotatable water wheel is a liquid pump that removes liquid from the condenser apparatus. An electric motor is utilized for rotatably driving all of the rotating elements. The condenser apparatus is utilized particularly in an automatic clothes dryer wherein hot moisture-laden air that has been passed over the fabrics to be dried is introduced into the condenser apparatus which reduces the temperature of the air when it passes through the liquid droplet cloud to condense moisture therefrom and then recirculates the air again through the clothes dryer.

CONDENSER APPARATUS

BACKGROUND OF THE INVENTION

1. Field of the Invention

This invention relates to condenser apparatus, and more particularly to condenser apparatus for utilization in an automatic clothes dryer so that warm moisture-laden air from the clothes dryer is cooled and moisture removed therefrom.

2. Description of the Prior Art

In automatic clothes dryers it is common to vent the warm moisture-laden exhaust air or vapor outside the machine and preferably even outside the house or building while air is constantly being introduced into the clothes dryer, heated and passed over the fabrics to be dried. It is not, however, always possible and, in fact, it may not be desirable to provide such a venting system for automatic clothes dryers in apartments or other high rise housing establishments. In drying fabrics in a clothes dryer it is highly desirable to be able to heat the air, pass the heated air over the fabrics to be dried and withdraw moisture therefrom, remove the hot moisture-laden air from the fabrics and introduce it into an apparatus that lowers the temperature of the moisture-laden air thereby condensing out moisture from the air, then recirculate the air through the clothes dryer.

Condensing apparatus has been utilized in laundry machines, both combination clothes washers and dryers and automatic clothes dryers, for many years. One such condensing apparatus is shown in U.S. Pat. No. 2,451,692 wherein moist air is passed through a water spray from a nozzle that is also used to effect movement of the air; the free water from the spray is to be removed by a stationary screen. Another type of condensing apparatus is disclosed in U.S. Pat. No. 2,785,557 wherein only a controlled portion of the moist air is passed through a dehumidifier. U.S. Pat. No. 2,921,384 shows apparatus that uses an impeller to circulate air that also has the cooling water discharged directly against the impeller, however, there is no free water collection means provided. U.S. Pat. No. 3,121,000 utilizes a condensing arrangement that produces a coherent film of water on a channel wall to avoid entrainment of water droplets.

Condenser apparatus for automatic clothes dryers must be efficient in operation, low in manufacturing cost, and economical to operate in order to make it desirable. Moreover, it should be compact and of a size such that it can be easily installed in present standard size clothes dryers.

To accomplish the above-mentioned desirable characteristics in a condenser apparatus, one of the main areas that has needed improvement is a means for producing a highly effective liquid droplet cloud through which the hot moisture-laden air from the dryer is passed. Such a droplet producing means must be capable of forming a high concentration of discrete relatively large liquid droplets to lower the temperature of the moisture-laden air as quickly as possible while it is passing through the droplet cloud. If the droplets are too small in size they are readily entrained by the air. Entrainment of free liquid is particularly troublesome when the blower that induces the air flow through the condenser apparatus is downstream from the liquid droplet cloud. Too much air entrainment of free liquid can detrimentally affect the efficiency of the entire condenser apparatus. Also, since the condenser appa-

ratus may be utilized in an automatic clothes dryer it is desirable to minimize expelling free liquid from the condenser apparatus into the clothes dryer system. Moreover, since the condenser dryer may be adapted for installation into present standard size clothes dryers, the condensing chamber containing the liquid droplet cloud must necessarily be limited in axial length. Therefore, to accomplish the necessary air cooling over the limited axial length, the liquid droplet dispersion means directly affects the efficiency of the entire condenser apparatus and the clothes dryer wherein it is utilized.

Rotating discs for producing liquid droplets have been used in apparatus for humidifying air. See, for example, U.S. Pat. No. 1,730,866 where atomized water impinges upon the disc downstream of the fan to be further broken up into a fine mist or vapor. U.S. Pat. No. 1,914,812 also uses a disc downstream of the fan to spread finely divided water particles throughout the atmosphere of a room. The arrangements shown in those patents, however, are specifically to provide for increasing the amount of moisture by producing finely divided water particles and expelling them from a humidifier into a room for humidification.

Multiple rotating discs have also been used to produce liquid droplets. See for example, U.S. Pat. Nos. 3,282,575 and 3,276,189. These patents, however, do not provide any means for distributing equal quantities of liquid to each of the discs. Without such equal distribution of liquid the efficiency of the discs in producing liquid droplets is detrimentally affected.

SUMMARY OF THE INVENTION

In condenser apparatus for removing moisture from the air by passing moisture-laden air through a condensing chamber having a cloud of cooling liquid droplets that are formed by liquid being thrown centrifugally from surfaces of a plurality of discs, there is provided an improved liquid droplet forming device. The improved device includes a rotatable liquid reservoir, a stack of axially spaced discs mounted on a rotatable shaft, and at least one channel for each disc in liquid flow communication between the reservoir and a liquid passage way from the channel to the surface of the respective disc. The channels have their forward ends terminated at the reservoir in alignment as viewed in a plane perpendicular to the shaft's axis of rotation and with the portions of the channels in the reservoir all substantially the same width and equally spaced.

Liquid from the reservoir is distributed to the channels and is acted upon by centrifugal force which causes it to flow in the channels to the liquid passage way of the respective disc where it passes through the passage way and onto the rotating disc, then moves to the periphery of the disc to be radially thrown from the periphery in the form of droplets.

It is an object of this invention to provide an improved rotatable multiple disc arrangement for producing liquid droplets.

It is another object of this invention to provide an improved rotatable multiple disc arrangement for producing liquid droplets for use in condenser apparatus which in turn may be used in an automatic clothes dryer.

It is also an object of this invention to provide an improved rotatable multiple disc arrangement for produc-

ing liquid droplets that has substantially equal quantities of liquid distributed to each disc.

It is also an object of this invention to provide a condenser apparatus which is simple in construction, efficient in operation, and compact in size to enable its incorporation into standard size automatic clothes dryers.

BRIEF DESCRIPTION OF THE DRAWINGS

FIG. 1 is a side elevational view of an automatic clothes dryer suitable for incorporation of the condenser apparatus utilizing the present invention, the view being partly broken away and partly in section to illustrate details.

FIG. 2 is a view taken along the lines 2-2 of FIG. 1 showing the condenser apparatus installed in the automatic clothes dryer.

FIG. 3 is a side elevational, cross-sectional view of the condenser apparatus utilizing the invention.

FIG. 4 is a partially cut away perspective view of the stack of multiple discs.

FIG. 5 is a cross-sectional view of the rotatable shaft taken in a vertical plane through the central longitudinal axis of the shaft.

FIG. 6 is an enlarged cross-sectional view of the rotatable shaft as viewed in a plane perpendicular to the longitudinal axis of the shaft taken along lines 6-6 of FIG. 5.

FIG. 7 is an enlarged cross-sectional view of how the 30 discs are mounted on the shaft.

DESCRIPTION OF THE PREFERRED EMBODIMENT

Referring now to the drawings and initially to FIG. 1 thereof, there is illustrated a domestic automatic clothes dryer 10 including an appearance and protective outer cabinet 11 having a door or closure 12 to provide access into the interior of the cabinet for loading and unloading fabrics. Provided on the top 13 of cabinet 11 is a control housing 14 which may, in a conventional way, include a suitable manual control 15 connected to a control assembly 16 mounted in the control housing 14. By manual setting of control 15, the machine may be caused to start and automatically 40 proceed through a cycle operation.

Within cabinet 11, there is provided a clothes tumbling container or drum 17 mounted for rotation on a substantially horizontal axis. Drum 17 is substantially cylindrical in shape, having a central cylindrical wall portion 18, and outer cylindrical wall portions 19 and 20, located respectively adjacent an annular front wall 21 and a circular rear wall 22 of the drum. Wall portions 18, 19 and 20 are imperforate while rear wall 22 has a plurality of perforations 33. On the interior surface of wall portion 18 there is a plurality of clothes tumbling ribs 23 so that clothes are lifted up when the drum rotates, and then permitted to tumble back down to the bottom of the drum. The front of the drum 17 may be rotatably supported within outer cabinet 11 by suitable slide members or idler wheels, one of the latter of which is indicated by the numeral 24.

The rear end of drum 17 receives its support by means of a stub shaft 27 extending from the center of wall 22. Shaft 27 is secured within a bearing 28 mounted in a baffle like structure 29 which, in turn, is rigidly secured to the back wall 30 of the cabinet 11.

In order to provide for the flow of drying air through the clothes drum, it is provided with a central aperture 32 in the front wall 21 and a plurality of perforations 33 in the rear wall 22. The air provided to the drum is heated as by an electrical resistance heating element 37, the element being the form shown in the drawings, which issues from the outlet 34 of the heating unit 35. Heating unit 35 includes a heater housing 36 and the electrical resistance heating element 37. In the conventional way, air is drawn into the heating unit 35 through an inlet opening 38 (FIG. 2) and is warmed as it passes over and through the electrical resistance heating element 37 and then out the heater outlet 34.

The outlet end 34 of the heating unit communicates with an upwardly extending duct 45, which enters a generally circular heat diffuser chamber 47 formed between the structure 29 and the rear wall 22 of drum 17. A flexible circumferential seal 39 is interposed between member 29 and rear wall 22 of the drum to provide a rear drum airseal and is secured to member 29 and contacts the rear wall of the rotating drum. The heated air flows from the chamber 47 through the perforations 33 into the interior of the drum 17.

The front opening 32 of the drum is substantially closed by means of a bulkhead generally indicated by the numeral 50. Bulkhead 50 is made up of a number of adjacent members including the inner surface 51 of the access door 12, a stationary frame 52 formed as a flange on front wall 46 of the cabinet and a front door liner 42.

A transition duct 62 is formed by joining together cavity member 54 and cavity member 53 at an annular flange 55. It will be noted that a suitable clearance is provided between the inner edge of aperture 32 and the edge of frame 52 so that there is no rubbing between the drum and the frame during rotation of the drum. In order to prevent substantial air leakage through the aperture 32, a suitable front drum ring seal 56 is secured to the flange 65 in sealing relationship with the exterior surface of the drum wall 21.

Door 12 is mounted on cabinet 11 so that when the door is opened fabrics may be inserted into and removed from the drum through the door frame 52.

The air outlet from the drum is provided by a perforated opening 59 formed in the inner wall 51 of the hollow door. The bottom wall section of door 12 and the adjacent wall of door frame 52 are provided with aligned openings 60 and 61, opening 61 providing an entrance to the duct 62. A lint trap 63 may be positioned in the duct 62 within opening 61 and supported by the door frame 52. Duct 62 leads downwardly and communicates with condenser housing 64. It is within the condenser housing that the hot moisture-laden air is cooled which causes moisture to be removed from the air prior to reintroducing the air into the heating unit 35 and then recirculated through the clothes dryer.

With reference to FIGS. 1 and 3 in particular, the operation and construction of the condenser apparatus will now be explained. The condenser apparatus includes a housing 64 which is cylindrical or drum shaped and has an air inlet 66 located at the front of the condenser unit which is also near the front of the clothes dryer. Hot moisture-laden air from the drum is introduced into the condenser unit through the air inlet 66 by a transition duct 62 (FIG. 1) between the drum and the air inlet. Also located at the same end of the condenser housing 64 is a liquid inlet means 70 which may

conveniently be a hose or tubular conduit 72 supported by structure 74 secured in a suitable fashion to the condenser housing. The structure 74 secures and positions the tubular conduit 72 substantially on the longitudinal axis of the condenser housing 64 with the end 73 of the conduit 72 directed into the condenser apparatus. The liquid introduced into the condenser apparatus by means of the tubular conduit 72 passes through a solenoid operated control valve (not shown) and is in the form of a stream. The liquid is furnished from a source external of the clothes dryer such as a household faucet.

Spaced axially from the liquid inlet means 70 is my improved multiple disc liquid droplet forming device. The details of the device can be clearly seen in FIGS. 4-7. A rotatable shaft 140 has a rear portion 142 adapted to receive the motor shaft 115 as by a receiving cavity 144 that accommodates the motor shaft which may be secured thereto by any suitable means, such as a set screw (not shown). This securing then provides for rotation of the shaft 140 along with rotation of the motor shaft 115 when the motor is energized. The forward portion 146 of shaft 140 has a liquid reservoir 148 that may be integrally formed with the shaft and is adapted to receive liquid from the liquid supply means 70. To accomplish introduction of liquid into the reservoir 148 there is a hollow end connector 150 that is suitably secured at one end to the forward portion 146 of shaft 140. The connector 150 has an end wall 151 with an opening 153 at the end opposite the shaft which is utilized to receive the end 73 of the liquid conduit means 72. In this manner then liquid flowing from the liquid supply means through conduit 72 passes into connector 150 and by communication between connector 150 and the reservoir 148 liquid is provided to the reservoir 148.

A number of channels that may be in the form of grooves 152 are located around the outer surface 154 of shaft 140. These grooves 152 have their forward ends 155 terminated at the reservoir 148 in alignment as viewed in a plane perpendicular to the shaft's axis of rotation. This plane is designated A in FIG. 5. The portion of the grooves in the reservoir 148 are all of substantially the same width and equally spaced around the shaft. While the portion of the grooves not in the reservoir may be of varying shapes and dimensions, in the preferred embodiment these grooves are conveniently cut or otherwise formed in the shaft 140 and are substantially parallel to the axis of rotation of the shaft. These grooves throughout their length are also of substantially the same width at the top 156 where the grooves 152 and the outer surface 154 of the shaft meet and the bottom 158 of the grooves are also substantially the same width and can be of any configuration. The grooves should, of course, be dimensioned to accommodate a sufficient amount of liquid for the desired liquid flow.

Positioned on and secured to the shaft 140 are a number of discs 160, which may conveniently all be of the same configuration. Each disc 160 has a hub 162 through which the rotatable shaft 140 passes. The discs are dished and have a continuous wall 164 slanting upwardly and outwardly relative to the hub 162 with the inside surface 161 facing toward the shaft reservoir 148. The continuous wall 164 terminates at a circular lip or periphery 166. The rearward surface 168 of the continuous wall 164 has a circular collar portion 170

projecting rearward and is slightly larger in diameter than the hub 162. The hub 162 of each disc has at least one aperture 172 through the hub forwardly of the continuous wall 164 of the disc.

The discs 160 are placed on the rotatable shaft 140 by passing the shaft through the respective hubs. The discs are secured in any suitable manner to the rotatable shaft 140 such that the aperture 172 through the hub 162 is in alignment with a groove 152 in the rotatable shaft. Each aperture 172 being aligned with a different groove 152 should be large enough to allow the desired amount of liquid to flow through them. With reference particularly to FIG. 7, when the discs are mounted on the shaft they are spaced apart by the terminal end 165 of hub 164 abutting a shoulder 167 of the hub on the next successive stacked disc at joining area 169. By this structure there is provided a liquid flow passageway from the groove 152 to the inside surface 161 of the disc wall 164. As shown by arrows in FIG. 7 the liquid from the groove 152 flows through aperture 172 of the hub into a circumferential channel area 173 formed between two adjoining discs and onto the disc inside surface 161. By this alignment then liquid flowing along a groove is in communication with its rotatable disc through the respective aperture 172. Preferably each disc 160 will have two apertures 172 through the hub 162 and they should be opposite each other. This means then that two grooves will be in communication with each disc through the two respective apertures. The reason for this arrangement is that better distribution of liquid to the continuous wall 164 of the discs 160 is accomplished. As shown in FIGS. 4, 5 and 6 in my preferred embodiment, a multiple stack of discs includes six discs and the rotatable shaft 140 has two grooves per each disc. It will be appreciated that each disc is oriented so that two different grooves are utilized per disc.

The operation of my multiple stack disc arrangement 40 is as follows: During operation of the condenser apparatus with the motor energized shaft 115 will rotate rotatable shaft 140 carrying with it all of the stacked discs 160 and also the connector 150. As liquid is introduced through the liquid inlet means 70 through conduit 72 45 into the connector 150 the liquid will pass into shaft reservoir 148 and by centrifugal force form a film or sheet of liquid around the inner wall surface 174 of the reservoir and will flow rearwardly until it contacts the portion of the grooves 152 in reservoir 148. The liquid is caused to enter the grooves by centrifugal force as the grooves rotate with the shaft. The shaft reservoir may have a cone shaped rearward wall 176 to help direct the liquid into the grooves. These grooves provide a channel through which the liquid will flow into the 50 mounted disc area. The liquid flowing through the grooves continues by centrifugal force rearward until it reaches the disc that has its aperture 172 aligned and in communication with that respective groove whereupon again by centrifugal force the liquid will be forced through the aperture and disc passageway onto the inside surface 161 of the continuous wall 164 thereof. It should be noted that what is accomplished by this 55 groove and disc arrangement is that equal quantities of liquid are automatically measured and distributed to each of the axially stacked discs. The operation of forming the liquid droplets with this axially stacked disc arrangement will be described later.

At the opposite end of the condenser housing 64 from the liquid inlet means 70 is a blower 78 for inducing air to flow from the air inlet 66 to an air outlet 80. The blower 78 not only induces air flow through the condenser apparatus but causes the air to flow through the entire clothes dryer so that only a single blower is needed. The blower in this embodiment consists of a rotatable blower wheel having a plurality of blades 82 secured as by molding to circular plate 83 and a confining air space 84 surrounding the blower wheel for developing sufficient air pressure within the blower to induce the above-mentioned air flow through the entire clothes dryer including the condenser unit. Positioned within the condenser housing 64 and located between the stack of multiple rotatable discs 76 and the blower 78 is a liquid droplet collecting means 86 which in the present preferred embodiment described is in the form of a rotatable water wheel having a plurality of spaced blades 88 which extend radially outward from the axis of rotation of the wheel. The axial depth of blades 88 is such that they extend from the blower wheel 78 into the condensing chamber 90. The blades 88 are integrally formed with a hub 92 and are spaced so that air flowing through the condenser apparatus may flow through the spaces between the radial blades 88 and into the blower. Surrounding the water droplet collecting means 86 is a pump 94 which consists of a rotatable U-shaped inner wall 96 and a stationary outer pump wall 98 which cooperate with each other to provide a pump cavity 100 therebetween. The outer pump wall 98 may be integrally formed with the condenser housing. Also forming one part of the pump 94 is a circumferential wall member 99 that is stationary and secured to the inside of the condenser housing and inwardly depending therefrom. Rotation of the inner pump wall 96 forces the liquid to be accelerated circumferentially by rotational force and discharged through the pump discharge outlet 102. The discharge outlet 102 (FIG. 2) is connected by suitable means to a drain outside of the clothes dryer.

Located at the bottom of the condenser housing 64 is a sump 104 which performs as an auxiliary liquid discharge outlet from the condenser apparatus should the pump 94 fail to operate. The sump 104 consists of a reservoir 106 formed by surrounding a wall area 108. Plumbing codes generally require a sufficient air gap in association with the water inlet, so that if a negative pressure is produced in the water line, only air will be taken in. For this purpose, the sump may have a liquid discharge outlet (not shown) arranged to be spaced from and located below the liquid inlet means 73 to provide an air gap therebetween. If desired, means for discontinuing operation of the condenser apparatus responsive to the auxiliary liquid discharge may be provided. One such means could be an externally located float mechanism activated by overflow liquid discharged from the condenser.

At the rear of the condenser housing 64 is a rear wall 110 which forms part of the condenser housing. The rear wall 110 together with cylindrical wall section 111 of housing 64 and inwardly directed circular flange 113 form the blower chamber 84. Secured to the rear wall 110 on the opposite side from the blower chamber 84 is an electric motor 112 which may be suitably attached to the rear wall as by bolts 114. The electric motor has a rotatable shaft extending through an aperture 116 in the rear wall 110 close to the central longitudinal axis

of the condenser apparatus. Secured to this motor shaft 115, which extends into the condenser housing, are the four rotatable elements of the condenser apparatus, namely, the blower 78, the water droplet collecting means or water wheel 86, inner wall 96 of the pump 94 and the stack of multiple discs 76. The single motor 112 rotatably drives all four of these condenser apparatus elements.

The motor shaft 115 also extends rearward of the motor in the opposite direction from the condenser apparatus and is utilized to rotate drum 17. In order to effect this rotation, motor 112 is provided with a shaft portion 118 having a small pulley 120 secured to the end thereof. Around the pulley 120 and seated in groove 121 and entirely around the cylindrical wall section 18 of drum 17 is a movable belt 122. The relative circumference of the pulley 120 and the wall section 18 of the drum 17 causes the drum to be driven by the motor at a speed suitable to effect tumbling of fabrics to be dried in the drum. In order to effect proper tensioning of the belt 122, a suitable idler assembly 124 is secured to the same support 126 which supports one end of the motor.

The air exiting the condenser apparatus through air outlet 80 passes via duct 128 into the heating unit 35 for heating the air and recirculating it into the clothes dryer drum 17.

The operation of the condenser and dryer apparatus is as follows: Hot moisture-laden air that has been passed through the clothes dryer drum and picked up moisture from the fabrics tumbled therein is introduced into the condenser unit through the air inlet opening 66 while a stream of cooling liquid is being introduced into the condenser unit through tubular conduit 72. When the condenser apparatus is operating the electric motor provides for simultaneous rotation of the blower 78, droplet collecting water wheel 86, inner wall 96 of pump 94 and disc 76. As the stacked axially spaced discs 160 mounted on the shaft 140 are rotated with the shaft, liquid from the grooves 152 is distributed through the respective apertures 172 of each disc onto the inside surface 161 of continuous wall 164 where it is acted upon by centrifugal force causing the liquid to spread into a film or sheet and swirl and travel up the inclined inner wall surface of the disc 160 to the periphery 166 thereof and from there thrown outwardly in the form of liquid droplets 130. The generally radial flight of the liquid droplets 130 is interrupted by the inner surface 132 of the condensing chamber 90 whereupon the liquid droplets are deflected back toward the center of the condenser chamber, this in effect produces a curtain or cloud of liquid droplets within the condensing chamber 90 while the incoming hot moisture-laden air from the dryer drum flows through this resultant liquid droplet cloud.

With my multiple disc arrangement an equal quantity of liquid is distributed to each of the discs thus affording a highly effective liquid droplet forming operation. The hot moisture-laden air in contact with the cooler liquid droplets causes the air temperature to be lowered and the moisture condensed therefrom. Because the air flowing through the condenser chamber 90 may entrain some liquid droplets the water droplet collecting means 86 is positioned upstream of the blower 78 between the disc 76 and blower 78 so that entrained liquid droplets are essentially collected by the rotating blades 88 and deposited in an underlying liquid bath

133 which is in communication with the pump 94 through an opening 134. It will be understood that simultaneously with the introduction of cooling liquid into the condenser apparatus through the tubular conduit 72 that liquid will also be removed from the condenser apparatus by the pump 94 at a rate such that only a small amount of liquid is in the liquid bath 133 at a given time during operation of the condenser apparatus. The now cooled air reaches the blower 78 which applies air pressure to induce the air flow and force the air out of the condenser apparatus through air outlet 80 for introduction into the heating unit 35 and again recirculate through the clothes dryer.

The foregoing is a description of the preferred embodiment of the invention and variations may be made thereto without departing from the true spirit of the invention, as defined in the appended claims.

What is claimed is:

1. An improved liquid droplet forming device comprising:

- a. a rotatable liquid reservoir,
- b. a plurality of discs axially stacked and spaced from each other mounted on a rotatable shaft, and
- c. a plurality of channels with at least one channel in liquid flow communication between the reservoir and each disc, said channels having their one end terminated at the reservoir in alignment as viewed in a plane perpendicular to the shaft's axis of rotation and the portions of the channels in the reservoir all substantially the same width and equally spaced.

2. The improved liquid droplet forming device of claim 1 wherein each disc has a hub securing the disc to the shaft, said hub having an aperture therethrough in communication with a single channel.

3. The improved liquid droplet forming device of claim 1 wherein each disc is dished with the inside surface thereof directed toward the reservoir.

4. The improved liquid droplet forming device of claim 2 wherein two apertures are provided in the hub each on opposite sides of the hub from each other and each in communication with a single channel.

5. The improved liquid droplet forming device of claim 1 wherein the liquid reservoir is integrally formed with the shaft.

6. The improved liquid droplet forming device of claim 1 wherein the channels are grooves formed in the shaft and are parallel to the shaft's axis of rotation.

7. In condenser apparatus for removing moisture from air by passing moisture-laden air through a cloud of cooling liquid droplets that have been formed by liquid being thrown centrifugally from surfaces of multiple discs, an improved liquid droplet forming device comprising:

- a. a rotatable liquid reservoir,
- b. a plurality of discs axially stacked and spaced from each other mounted on a rotatable shaft, and
- c. a plurality of channels with at least one channel in liquid flow communication between the reservoir and each disc, said channels having their one end terminated at the reservoir in alignment as viewed in a plane perpendicular to the shaft's axis of rotation and with the portions of the channels in the reservoir all substantially the same width and equally spaced.

8. In the condenser apparatus improvement of claim 7 wherein each disc has a hub securing the disc to the shaft, said hub having an aperture therethrough in communication with a single channel.

9. In the condenser apparatus improvement of claim 7 wherein each disc is dished with the inside surface thereof directed toward the shaft reservoir.

10. In the condenser apparatus improvement of claim 7 wherein two apertures are provided in the hub each on opposite sides of the hub from each other and each in communication with a single channel.

11. In the condenser apparatus improvement of claim 7 wherein the liquid reservoir is integrally formed with the shaft.

12. In the condenser apparatus improvement of claim 7 wherein the channels are grooves formed in the shaft and are parallel to the shaft's axis of rotation.
